UNITED STATES PATENT OFFICE.

JOHN A. MACKRODT, OF OAKLAND, CALIFORNIA, ASSIGNOR TO INTERNATIONAL DEVICES INC., OF OAKLAND, CALIFORNIA, A CORPORATION OF CALIFORNIA.

WRAPPING-PAPER CABINET.

Application filed May 17, 1922. Serial No. 561,612.

To all whom it may concern:

Be it known that I, JOHN A. MACKRODT, a citizen of the United States, residing at Oakland, county of Alameda, and State of California, have invented new and useful Improvements in Wrapping-Paper Cabinets, of which the following is a specification.

This invention relates to cabinets and especially to cabinets designed for the receptions of rolls of wrapping paper of different widths and diameter, and which is provided with a panel through which the paper can be pulled out and torn off in desired lengths.

The object of the present invention is to generally improve and simplify cabinets of the character described, and especially to provide a front panel through which the paper is passed, pulled out and torn off at desired lengths; also to provide novel means for clamping and securing the paper while it is being torn and for retaining the torn end in a position where it may be readily and quickly grasped when more paper is desired. Further objects will hereinafter appear.

One form which my invention may assume is exemplified in the following description and illustrated in the accompanying drawings, in which—

Fig. 1 is a front view of the cabinet.

Fig. 2 is a central, vertical cross section on line 2—2, Fig. 1.

Fig. 3 is an enlarged view of the knife and the gate cooperating therewith.

Referring to the drawings in detail, A indicates in general a cabinet, consisting of side sections 2 and 3, a top and bottom, as indicated at 4 and 5, respectively, a back section 6, and a front panel 7. Disposed within the cabinet and supported by superposed rollers, as indicated at 8 and 9, are rolls of wrapping paper shown at 10 and 11, respectively. To permit the rolls to be readily replaced, a hinged connection 12 is formed between the front panel and the cabinet to permit the cabinet to be opened. The rolls 8 and 9 are supported by end cleats 13, which are slotted longitudinally and vertically as at 14 and 15. The rolls are in this manner inserted endwise and are dropped into the vertical slots 15, which form bearings therefor, the rolls of wrap-

ping paper being loosely supported on top of the rolls and the paper may thus be freely unwound as needed.

Forming an integral part of the front panel, or secured thereto, adjacent the upper end, is a pair of superposed interspaced cross bars 16 and 17. The back of each bar is curved and angularly disposed, as at 18, to form a pair of pockets 19 and 20, as clearly illustrated in Fig. 2. The upper ends of the members 18 are spaced with relation to the cross bars 16 and 17, and openings 21 are thus formed through which the paper from the respective rolls may be passed. The cross bars, and the members 18 forming a part thereof, extend from side to side of the panel and thus form elongated horizontally disposed openings through which the paper may be passed. The cross bar 17 forms the upper side of the pocket 19 and the slot or opening 21, and a cross bar 22 forms the upper side of the pocket 20 and the adjacent longitudinal opening 21. A cutting blade is arranged longitudinally of each pocket and in the upper portion thereof, and these cutting blades, as shown at 23, are secured in any suitable manner to the respective cross bars; the paper being passed under the lower edges of the blades and being torn along their edges when required.

For the purpose of retaining the end of the paper when torn, and to prevent the paper from falling back into the cabinet, a combined closure and clamping means is employed in connection with each pocket. These closures will hereinafter be termed "gates." They extend from end to end of each pocket, as shown at 24 and 25, see Figs. 1 and 2. Their lower ends are hingedly secured to the respective cross bars 16 and 17, as at 26, and their upper ends engage the inner sides of the knives 23, see particularly Fig. 3. The face of each gate is rounded or concaved, as shown at 27, and each gate is normally held in engagement with its respective knife by means of a helical spring 28. To further secure the ends of the paper strips against being accidentally retracted, a pair of tension rolls 30 and 31 is provided. The ends of these rolls are received and guided by angular slots or recesses formed in the ends of the front panel and may thus be lifted into or out of engagement with

the upper ends of the members 18 when the paper is being inserted. They otherwise rest on top of the paper and the weight imposed is more than sufficient to retain the paper.

In actual practice when the rolls have been inserted, it is only necessary to pass the ends of the strips over the upper ends of the members 18, which form a guide therefor, care being taken that the paper is passed below the rollers 30 and 31 so that their weight may be imposed upon the paper. The free ends of the paper are then passed over the upper edge of the gates 24 and 25 and passed in under the cutting edges of the knives 23, the gates being depressed or forced back to the dotted line position shown at 32 during this operation. The gates may then be released and the paper will be clamped between the rear side of the cutting blades and the front or upper edge of the respective gates, a double lock or grip being in this manner provided which prevents accidental release or retraction of the paper. If paper is required, it is only necessary to place the fingers against the curved faces of one gate or another and to depress the same as indicated at 32. The paper is in this manner released with relation to the gate and the cutting blade, and the free end will drop by gravity and will assume the dotted line position indicated at 33. It may here be readily grasped by the fingers and any length may be pulled out as desired, care being taken that the paper is pulled in a downward direction as such a pull will tend to hold the gate in a depressed position. The moment a desired length has been withdrawn, it is only necessary to pull the paper upwardly against the cutting blade. The gate will during this movement of the paper swing forward and clamp the paper against the knife, thus holding it securely during the cutting or tearing operation, and it will at the same time retain the free end of the paper so that it may be conveniently grasped when more paper is required.

By referring to Fig. 3, it will be noted that the upper ends of the gates are disposed on an angle as indicated at 34. This is of considerable importance, first because it places a double kink in the paper, as indicated at 35 and 36, when the tearing operation takes place, and secondly because it forms an inclined face which has a tendency to force the gate inwardly when a downward pull is exerted on the paper, as indicated by dotted lines at 33, that is the gate must remain open while the paper is being withdrawn, and such open position of the gate is automatically maintained by inserting a downward pull on the paper as the inclined upper edge of the gate will then coact with the paper to maintain the

gate in an open position. An upward pull on the paper will tend to release the gate and it will thus swing forward as shown in Fig. 3 and clamp the paper against the inner face of the cutting blade, and it will at the same time put a double kink or fold in the paper which increases the efficiency of the clamping action, and also places the paper in a position where it may be readily cut or torn.

The cabinet may also contain one or more balls of twine, as shown at 40, and this may be extended upwardly and passed through an opening 41 in the panel, from where it may be withdrawn and cut in any suitable manner.

In the present instance it will be seen that the pockets 19 and 20 extend from end to end of the panel. This is only necessary when wide rolls of paper are employed. If narrow rolls are desired, it is obvious that each pocket may be divided into two or more compartments so that paper of various widths may be taken care of.

While certain features of the present invention are more or less specifically illustrated, I wish it understood that various changes in form and proportion may be resorted to within the scope of the appended claims, similarly that the materials and finish of the several parts employed may be such as the experience and judgment of the manufacturer may dictate or various uses may demand.

Having thus described my invention, what I claim and desire to secure by Letters Patent is—

1. A device of the character described comprising a cabinet, a paper roll mounted therein, a front panel forming a closure for the cabinet, said panel having a relatively narrow transverse opening formed therein through which the paper is passed, a knife extending from end to end of the opening and disposed in the upper side thereof, and a gate pivotally mounted in said opening and forming a closure for said opening, the upper edge of said gate being engageable with the knife and adapted to clamp the paper against the knife when in closed position, the upper edge of said gate being forwardly inclined and forming a support and guide for the paper, and said gate adapted to be depressed and opened when a downward pull is exerted on the paper.

2. In a cabinet of the character described means for supporting a paper roll, a panel, a cross bar in the panel, an inclined member on the cross bar forming a guide over which the free end of the paper from the roll is adapted to be passed, said cross bar and inclined member forming a relatively narrow opening in the panel through which the paper may extend, a knife disposed adjacent the upper side of said opening, and a

weighted roller engaging the paper and adapted to be supported by the upper edge of the guide.

3. In a cabinet of the character described 5 means for supporting a paper roll, a panel, a cross bar in the panel, an inclined member on the cross bar forming a guide over which the free end of the paper from the roll is adapted to be passed, said cross bar and inclined member forming a relatively narrow transverse opening in the panel through which the paper may extend, a knife disposed adjacent the upper side of said opening, a gate member hingedly secured along 10 its lower edge to the cross bar, and extending from end to end of the transverse opening, the free end of the paper adapted to pass over the upper edge of the gate and under the edge of the knife, and means for 15 normally holding the upper end of the gate in engagement with the knife to clamp the paper between the gate and the knife.

4. In a cabinet of the character described 20 means for supporting a paper roll, a panel, a cross bar in the panel, an inclined member on the cross bar forming a guide over which the free end of the paper from the roll is adapted to be passed, said cross bar and inclined member forming a relatively narrow 25 transverse opening in the panel through which the paper may extend, a knife disposed adjacent the upper side of said opening, a gate member hingedly secured along its lower edge to the cross bar and extending 30 from end to end of the transverse opening, the free end of the paper adapted to pass over the upper edge of the gate and under the edge of the knife, and means for 35 normally holding the upper end of the gate in engagement with the knife to clamp the paper between the gate and the knife, the upper edge of said gate being forwardly inclined to present an angular guide surface and to maintain the paper in a vertical, angular position with relation to the edge of 40 the knife when clamped by the gate member.

5. In a cabinet of the character described 45 a front panel having a relatively narrow transverse opening formed therein, a cross bar forming the bottom portion of said opening, said cross bar having a curved inwardly extending inclined guide member attached thereto, a weighted roller engageable with the upper end of the guide member, a 50 gate extending from end to end of the transverse opening, a hinged connection between the lower edge of the gate and the cross bar, a knife disposed adjacent the upper edge of the opening and the upper edge of the 55 gate adapted to engage the inner face of said knife, and means for normally maintaining the gate in engagement with the knife.

6. In a cabinet of the character described 60 a front panel having a relatively narrow transverse opening formed therein, a cross

bar forming the bottom portion of said opening, said cross bar having a curved inwardly extending inclined guide member attached thereto, a weighted roller engageable with the upper end of the guide member, a 65 gate extending from end to end of the transverse opening, a hinged connection between the lower edge of the gate and the cross bar, a knife disposed adjacent the upper edge of the opening and the upper edge of the 70 gate adapted to engage the inner face of said knife, a spring interposed between the gate and the guide member, and a curved surface formed in the forward side of the 75 gate.

7. In a cabinet of the character described 80 a front panel having a relatively narrow transverse opening formed therein, a cross bar forming the bottom portion of said opening, said cross bar having a curved inwardly extending inclined guide member attached thereto, a weighted roller engageable with the upper end of the guide member a 85 gate extending from end to end of the transverse opening, a hinged connection between the lower edge of the gate and the cross bar, a knife disposed adjacent the upper edge of the opening and the upper edge of the gate adapted to engage the inner face of said 90 knife, a spring interposed between the gate and the guide member, a curved face formed in the forward side of the gate and a forwardly inclined surface formed along the 95 upper edge of the gate.

8. In a device of the character described, 100 a cabinet, means for supporting a paper roll in the cabinet, the cabinet having one wall provided with a transverse opening therein, a member secured to the cabinet adjacent said opening and extending inwardly and 105 upwardly and forming a guide over which the free end of the paper from the roll is adapted to be passed to said opening, a knife disposed adjacent said opening, and movably mounted means located within the opening 110 and adapted to normally coat with the knife to hold the paper normally in engagement with the knife.

9. In a device of the character described, 115 a cabinet, means for supporting a paper roll in the cabinet, the cabinet having one wall provided with a transverse opening therein, a member secured to the cabinet adjacent said opening and extending inwardly and 120 upwardly and forming a guide over which the free end of the paper from the roll is adapted to be passed to said opening, a knife disposed adjacent said opening, movably mounted means located within the opening and adapted to normally coat with the 125 knife to hold the paper normally in engagement with the knife, and means arranged adjacent the upper edge of said guide member to coat with the aforesaid paper engaging means to hold the paper against retraction. 130

10. In a device of the character described, a cabinet, means therein for supporting a paper roll, the cabinet having a transverse opening in one wall thereof, a knife adjacent the upper side of said opening, a guide member adjacent said opening and projecting into the cabinet and over the upper edge of which the paper strip is adapted to be drawn, and a gate for normally closing said opening and adapted to coact with the knife to normally hold the paper strip in engagement with the knife, the gate being movable inwardly toward said guide member to permit withdrawal of the paper over said guide member through said opening.

11. In a device of the character described, a cabinet, means therein for supporting a paper roll, the cabinet having a transverse opening in one wall thereof, a knife adjacent the upper side of said opening, a guide member adjacent said opening and projecting into the cabinet and over the upper edge of which the paper strip is adapted to be drawn, a gate for normally closing said opening and adapted to coact with the knife to normally hold the paper strip in engagement with the knife, the gate being movable inwardly toward said guide member to permit withdrawal of the paper over said guide member through said opening, and means cooperating with the guide member and coacting also with the gate to prevent accidental retraction of the paper strip when the gate is holding the paper strip against said knife.

12. In a device of the character described, comprising a cabinet having an inwardly di-

rected pocket formed in the front thereof, the pocket being formed to provide an opening between the front wall and the pocket, means for loosely supporting a paper roll in the cabinet and through which opening the paper may be drawn, a knife disposed adjacent said opening, and a spring controlled gate mounted in said pocket for normally closing said opening and for binding the paper against the knife.

13. In a device of the character described, comprising a cabinet having an inwardly directed pocket formed in the front thereof, the pocket being formed to provide an opening between the front wall and the pocket, means for loosely supporting a paper roll in the cabinet and through which opening the paper may be drawn, a knife disposed adjacent said opening, and a gate mounted in said pocket for normally closing said opening and for binding the paper against the knife.

14. In a device of the character described, comprising a cabinet having an inwardly directed pocket formed in the front thereof, the pocket being formed to provide an opening between the front wall and the pocket, means for loosely supporting a paper roll in the cabinet and through which opening the paper may be drawn, a knife disposed adjacent said opening, a gate mounted in said pocket for normally closing said opening and for binding the paper against the knife, and means mounted over the pocket for engagement with the paper to hold the paper against retraction.

JOHN A. MACKRODT.
